J. S. WRIGHT.
VAPORIZER DEVICE FOR EXPLOSIVE ENGINES.
APPLICATION FILED JULY 9, 1917.

1,299,648.

Patented Apr. 8, 1919.

UNITED STATES PATENT OFFICE.

JOHN S. WRIGHT, OF OWENSBORO, KENTUCKY.

VAPORIZER DEVICE FOR EXPLOSIVE-ENGINES.

1,299,648.

Specification of Letters Patent.

Patented Apr. 8, 1919.

Application filed July 9, 1917. Serial No. 179,319.

To all whom it may concern:

Be it known that I, JOHN S. WRIGHT, a citizen of the United States, and residing at Owensboro, in the county of Daviess and

5 State of Kentucky, have invented a new and useful Improvement in Vaporizer Devices for Explosive-Engines, of which the following specification is a full disclosure.

My invention relates to internal combustion or explosive engines and in particular 10 to fuel supply devices in connection with the intake manifold of the engine for vaporizing hydro-carbon oils of different quality or kind.

15 An object of the invention is to provide the inlet manifold of an internal combustion engine with a fuel supply conduit extended into the exhaust manifold in a zig-zag or return bend course for heating and vaporizing 20 the fuel passing therethrough from one source of supply, and in providing the conduit with a branch inlet between that portion within the exhaust manifold and inlet manifold for admitting fuel from a second 25 source, rendering possible the use of different grades or kinds of hydro-carbon oils requiring different treatment for vaporizing, and permitting a transfer to be readily and quickly made, alternately from one kind to 30 the other.

Another object of the invention is to provide a deflected fuel supply conduit projected into the exhaust manifold of the engine for heating the products passing 35 through said conduit and draining any liquid products collecting in said conduit back to the inlet end.

A further object of the invention is to 40 provide a vaporizing device, as a return bend conduit forming a part of a supply line from the carburetor to the engine intake and internally providing an inclined wall as a heated baffle plate against which the hydro-carbon products entering the vaporizer may strike for assisting in vaporizing the same.

Other features and advantages of the invention in part relate to details of construction of various elements and their relation to one another in providing a manifold fuel supply system for utilizing different kinds and quality of fuel, and for readily vaporizing those of low volatile grade, all of 50 which will be more fully set forth in the description of the accompanying drawings,

forming a part of this specification, and in such drawings like characters of reference denote corresponding parts throughout the several views, of which:

Figure 1 is a side elevation of an explosive 60 engine with the portion containing my invention in section.

Fig. 2 is a section taken on an irregular line 2—2, Fig. 1, with a portion thereof at one end shown in elevation. 65

Fig. 3 is a detail central vertical section through a modified form of vaporizer device forming a part of the intake conduit leading from a carburetor to the intake manifold of the engine. 70

Fig. 4 is a detail central vertical section through another modified form of vaporizer device having transverse baffle webs functioning as means for breaking up the fuel. 75

Fig. 5 is a plan section on line 5—5, Fig. 4. 75

The engine in construction may represent any one of the numerous designs commercially known as either single, multiple or plural cylinders, of the two or four cycle type, and as the details of the engine construction do not enter materially into the present invention, description thereof will be omitted, excepting as to such parts of the engine as may be necessary for a clear understanding of the invention. 85

Referring to the drawings, 1 indicates the engine cylinder, 2 the fuel intake manifold having communication individually with each one of the engine cylinders of the series. The particular intake manifold shown, interiorly, for a portion of its length has a division wall 3, forming two adjacent passages 4 and 6. The passage 6 is about double the length of the passage 4 and communicates at a central point 5 with the end 95 of passage 4. This provides for a uniform distribution of the fuel to the various lead branches of the passage 6 respectively connecting with the inlet openings of the cylinders of the engine. The intake manifold is 100 shown as bolted to the engine cylinder heads in a removable manner. The exhaust manifold 7 is bolted to the cylinder heads and provided with conduit leads connecting with the respective exhaust ports of the several 105 cylinders. The exhaust manifold is shown as located directly beneath the intake manifold to bring the same to a lower elevation, the purpose of which will be later described; it increases in cross-sectional area toward 110

one end to house a vaporizer 8 inserted therein, whereby the exhausting hot gases are utilized to heat the vaporizer. The outlet port 9 of the exhaust manifold is located 5 in proximity to and at an elevation below the vaporizer, so that all the exhaust gases are directed against the vaporizer before escaping.

The vaporizer 8 in construction forms a 10 conduit return bend with an interior downwardly inclined division web 10 separating the conduit runs. The vaporizer fits into an opening in the end of the exhaust manifold and is provided with an abutting flange 11 at 15 its conduit ends for securing the vaporizer to the exhaust manifold and as a closure for the manifold opening. The side walls of the vaporizer are also spaced from the side walls of the manifold so as to expose the entire 20 circumference of the vaporizer to the heat of the exhaust gases of the engine.

The web 10 of the vaporizer qualifies as a heated baffle for the particles of liquid against which they strike as drawn into the 25 vaporizer, checking their course and vaporizing them. The lower surface of the web 10 may be provided with serrations or corrugations, as shown in the modified design, Fig. 3, as well as the upper inclined wall 30 of the return run of the vaporizer conduit. The vaporizer may further be provided with transverse baffle webs 25, as shown in the modified designs Figs. 4, 5, and which function as means for breaking up the fuel. All 35 the interior surfaces of the vaporizer are inclined in a direction which will result in draining any liquid rearwardly to the inlet end or into the carbureter 12. The carbureter 12 connects directly with the inlet port 40 of the vaporizer, and in construction may follow any commercial design or type for emitting air and a liquid fuel in a spray, with the suction created by the moving engine pistons or by fuel pump pressure. The 45 carbureter is provided with the usual regulatable needle valve for controlling the volume or amount of liquid fuel or vapor to the vaporizer.

The outlet port of the vaporizer connects 50 with a curved conduit 13, which in turn connects with the inlet ports of the intake manifold, or, as shown, with intake coupling conduit 14. Said coupling 14 has a valve 15 interposed therein for throttling the mixture 55 in the entrance to the intake manifold. The valve 15 may be of the butterfly-type shown, piston, rotating or any other style, manually or automatically operated or controlled, as may best meet the requirements.

60 The curved conduit 13 intermediately has a cylindrical valve body portion 16 with port openings for three ways, two of which establish the continuity of the passages through the conduit 13 from the vaporizer 8 to the 65 manifold intake, and a third port as a

branch to establish communication with a passage connection with the carbureter 17. The carbureter 17 provides the supply of a highly volatile liquid fuel or fuel of a different specific gravity than that supplied 70 from the carbureter 12, and which will vaporize without being passed through the heater.

For the purposes herein, it may be specified that carbureter 12 feeds kerosene as the fuel and carbureter 17 gasoline. 75

The carbureter 17, similar to carbureter 12, may represent any design or type of construction commercially known, so as not to require description specifically or in detail.

The valve body 16 is provided with a nipple projection 18 for securing the carbureter 17 and furnishes an entry port diagonally intermediate with the ports communicating with the conduit 13, so that communication may be alternately established through the 80 valve 19 with either carbureter 12 or 17. The valve 19 is of a rotary piston type, cylindrical, to fit the valve bore of the body with a way or conduit 20 therethrough, adapted to be brought into registry with the 90 various ports of the body. In the position shown in Fig. 1, the valve 19 is set to establish communication through the conduit 13 for taking the fuel supply from carbureter 12, cutting out carbureter 17. The valve 19 95 is shown as operated manually by a handle 21 and a one-third turn of the handle to the right will position the valve to close the port or branch of conduit 13 connecting with the vaporizer and carbureter 12 of the kerosene 100 line and establish connection with carbureter 17 and the opposite branch of conduit 13 leading to the intake manifold.

The fuel supply to the engine can be quickly 105 changed from one grade or quality to another by the control of valve 19, assuming that kerosene and gasoline represent the two different kinds of fuel used; and gasoline for starting purposes.

When the engine is cold the valve is shifted 110 to connect the intake manifold with the carbureter 17, after which, when the engine warms up, the valve may be shifted to cut out the carbureter 17 and connect carbureter 12 with the intake manifold, which fuel must 115 pass through the vaporizer 8 or a heated zone for heating the fuel products and converting the same into vapor, making the lower volatile fuel as efficient as the higher when it reaches the engine cylinder. 120

The vaporizer 8 is shown as tapped to receive pipe fitting 22 for admitting water or steam which is vaporized or superheated, as the case may be, as it is drawn through the vaporizer and mixed with the fuel products 125 coming from the carbureter 12.

The different kinds of fuel may also represent one kind but of different grades, as, for instance, what is commercially known as "high" and "low power" gasoline, in which 130

the higher-priced and grade oil can be used for starting and the lower for general or continued running of the engine.

Having described my invention, I claim:

- 5 1. The combination with an exhaust manifold of an explosive engine having an opening through one end thereof, a casing member projecting into said manifold through said opening and providing a closure therefor, said casing interiorly divided by an inclined wall and thereby forming a return bend conduit having its ends respectively connected to and in communication with a carbureter and intake manifold for heating 10 the products passing through said conduit from the carbureter to the intake manifold.
- 15 2. The combination with an exhaust manifold of an explosive engine, a casing member projecting through an opening in said manifold and flanged to provide a closure for said opening, said casing interiorly having an inclined wall providing a return bend 20 passage through said casing, the lower sur-

face of said wall providing a baffle for the incoming products and the upper surface a 25 return drain.

3. The combination with an exhaust manifold of an explosive engine having an opening therethrough at one end, a casing member projecting through said opening and into 30 the manifold and spaced from the walls of the manifold, said member having its upper outer wall inclined and interiorly divided by an inclined wall for forming a return bend conduit through the member, and the inclined walls forming baffles for fuel products 35 passing through said conduit, and a series of cross web baffles extending laterally of the conduit.

In witness whereof, I hereunto subscribe 40 my name, as attested by the two subscribing witnesses.

JNO. S. WRIGHT.
